PROCESS FOR THE PRODUCTION OF
1,2,3-TRICHLOROPROPENE

Louis F. Thetford, Jr., Charleston, and Joseph F. Lacount, South Charleston, W. Va., assignors to Union Carbide Corporation, a corporation of New York
No Drawing. Filed Mar. 23, 1960, Ser. No. 16,914
5 Claims. (Cl. 260—654)

This invention relates to a novel method for the production of 1,2,3-trichloropropene. 10

More specifically, the invention is concerned with the dehydrochlorination of 1,2,2,3-tetrachloropropene to obtain 1,2,3-trichloropropene.

The object of this invention is to provide an efficient economical process by which 1,2,2,3-tetrachloropropene can be converted to 1,2,3-trichloropropene.

The above object is accomplished by conducting the dehydrochlorination in the presence of an emulsifying agent.

1,2,3-trichloropropene is not a new compound. It is well known in the art. The method of making the above compound by dehydrochlorination of 1,2,2,3-tetrachloropropene is also known in the art.

The methods previously employed for dehydrochlorination of 1,2,2,3-tetrachloropropene included the use of aqueous sodium hydroxide, the use of aqueous sodium hydroxide and methanol, the use of sodium hydroxide and dioxane, and the use of methylethylpyridine residues.

However, these methods of effecting the reaction had at least two serious disadvantages. Poor conversion of 1,2,2,3-tetrachloropropene and/or low efficiency to the trichloropropene were obtained. Also, the crude reaction product frequently contained large amounts of impurities which could not be easily removed by refining.

Surprisingly, the above disadvantages have been found to be obviated when the dehydrochlorination is conducted in the presence of an emulsifying agent. The reaction proceeds at a rapid rate and the conversion of the 1,2,2,3-tetrachloropropene to 1,2,3-trichloropropene is higher than any of the known prior art methods. Additionally, the crude reaction product can be refined with comparative ease.

The following table illustrates the comparison of the prior art methods with the method of the instant invention.

TABLE I

Preparation of 1,2,3-Trichloropropene—Production From 1,2,2,3-Tetrachloropropene

Temp., °C.	Dehydrohalogenating Agent	Conversion, Percent 4CP	Efficiency to 3CP, Percent 4CP Basis 1
110	NaOH ²	16.04	53.85
50	NaOH—MeOH ³	89.6	47.9
140-160	MEP Residues ⁴	29.4	53.6
105	NaOH—Dioxane ⁵	29.1	46.1
103-120	NaOH ⁶	63.2	86.5

¹4CP is tetrachloropropene and 3CP is trichloropropene.

²Tetrachloropropene and sodium hydroxide were refluxed for six hours.

³A ten percent excess of equal weights of 50 percent sodium hydroxide and methanol fed to tetrachloropropene over a two-hour period.

⁴Tetrachloropropene was fed to 400 methylethylpyridine residues (catalyst) at the rate of 487 grams per hour per liter of methylethylpyridine residue.

⁵A ten percent excess of equal weights of 50 percent sodium hydroxide and dioxane added to tetrachloropropene and refluxed for five hours.

⁶Aqueous 20 percent sodium hydroxide fed to tetrachloropropene containing one weight percent Tergitol, at the rate of 140 g. per hour per liter of tetrachloropropene and allowed to reflux for one hour.

It can be seen that the use of an emulsifying agent gives efficiencies which are surprisingly better than the previously known methods.

2

Although a conventional emulsifying agent having a molecular weight in the range of 264 to 4000 can be used in the instant process, the preferred emulsifying agent is a Tergitol. Tergitol is a trademark of Union Carbide Chemicals Company for its surface active agents. There are two general types of these agents, anionic and nonionic. The anionic type are sulfates or phosphates of the C₈ to C₁₇ alcohols. The nonionics are ethylene oxide adducts of nonyl phenol, 2,6,8-trimethyl-4-nonal, and a butanol and ethylene oxide-propylene oxide adduct. The molecular weight range of the nonyl phenol adducts is 396-1100, that of the nonanol adduct is about 264 and that of the butanol adduct is from 2820 to 3414.

The term nonyl phenol is intended to mean a mixture of alkylated phenols whose substituents on the aromatic ring are predominately mixed ortho and para-isomers. The alkyl side chain of which is a mixture of branched isomers containing a varying number of carbon atoms (C₈, C₉, C₁₀) with the C₉ predominating.

20 A particularly preferred class of the above surface active agents are those having a molecular weight range of 525-975.

The amount of emulsifying agent used is about 0.1 to about 10 percent by weight based on the 1,2,2,3-tetrachloropropene. The preferred range is 0.5 to 5 weight percent.

25 The dehydrochlorinating agents employed are the alkali metal and the alkaline earth metal hydroxides. Specific examples include lithium hydroxide, sodium hydroxide, potassium hydroxide, calcium hydroxide, barium hydroxide and strontium hydroxide. The preferred reagent is sodium hydroxide.

30 The temperature at which the reaction is conducted is not narrowly critical. The preferred range is from about 100 to 140° C. at atmospheric pressure, although the kettle temperature may vary during the reaction. In a preferred embodiment of the invention, not only is the kettle temperature controlled, but the vapor temperature is also regulated. At atmospheric pressure, the vapor 35 temperature is maintained from about 93 to about 95° C. during reflux. It has been found that this range gives the highest efficiency.

35 The reaction can be conducted by mixing all the reagents together and refluxing, by adding the 1,2,2,3-tetrachloropropene to refluxing aqueous hydroxide containing the emulsifying agent or by the gradual addition of the hydroxide to a mixture of the emulsifying agent and the 1,2,2,3-tetrachloropropene. The latter method is the preferred one. In this method, the hydroxide is added in 40 the range of 0.01-0.5 mole per hour per mole of 1,2,2,3-tetrachloropropene. The preferred range is 0.05 to 0.1 mole per hour.

45 The concentration of the aqueous hydroxide solution employed is not narrowly critical. The preferred concentration is from about 20 to about 50 percent by weight.

50 In order to obtain the maximum efficiency to 1,2,3-trichloropropene it is desirable to remove the crude product as rapidly as it is formed. This is done to prevent the dehydrochlorination of the 1,2,3-trichloropropene to form 1,3-dichloropropene. This removal can be accomplished by any conventional manner such as distillation.

55 The following examples are illustrative of the instant invention.

EXAMPLE I

60 625 grams of 1,2,2,3-tetrachloropropene and 6.3 grams of Tergitol NP-35 (an ethylene oxide adduct of nonyl phenol with a molecular weight of about 880) was charged to a 2-liter kettle equipped with a sealed mechanical stirrer, thermowell, and sodium hydroxide feed tank. The kettle was placed on a 15-theoretical plate

column which was equipped with a decanting still head and receiver system. The receiver system was vented through cold traps.

The kettle contents were heated to 120° C. with stirring and aqueous 20 percent sodium hydroxide fed at the rate of 140 grams per hour per liter of tetrachloropropene. After refluxing for an hour, 1,2,3-trichloropropene was removed as lower layer of the water-trichloropropene azeotrope. The vapor temperature ranged from 93-94° C. during the reaction. The mole ratio of tetrachloropropene to total sodium hydroxide fed was about 1:1.

The crude 1,2,3-trichloropropene was refined on a 15-theoretical plate column. Cis- and trans- isomers are produced in the process in almost equal amounts. The 15 trichloropropene fraction was collected from 77.5-91° C. at 120 mm. Hg. Specific gravity of the fraction was 1.41 at 20/15.6° C. Conversion of tetrachloropropene was 63.2 percent and efficiency to trichloropropene was 86.5 percent based on tetrachloropropene.

EXAMPLE II

418 grams of 1,2,2,3-tetrachloropropene, 195 grams of 50 percent aqueous sodium hydroxide, and 19 grams of Tergitol E-68 (Tergitol NP-35 which has been etherified to remove the active hydrogen. The hydrogen has been replaced with an ethyl group to make a caustic-stable surface active agent) were charged to the apparatus described in Example I and heated to 130° C. for eight hours. 200 grams of water was added to the still kettle and the organic layer removed as lower layer of the azeotrope. Conversion of tetrachloropropene was 72 percent and efficiency to 1,2,3-trichloropropene was 76 percent based on tetrachloropropene.

EXAMPLE III

1226 grams of 1,2,2,3-tetrachloropropene and 13 grams of Tergitol NP-27 (an ethylene oxide adduct of nonyl phenol with a molecular weight of about 528) was charged to the apparatus described in Example I and 40 heated to 140° C. Aqueous 20 percent sodium hydroxide was fed at 155 grams per hour per liter of tetrachloropropene charged. Mole ratio of tetrachloropropene to total sodium hydroxide fed was about 1:1. Crude 1,2,3-trichloropropene was removed as lower layer 45

of water-trichloropropene azeotrope and refined as in Example I. Conversion of tetrachloropropene was 66 percent and efficiency to trichloropropene was 83 percent based on tetrachloropropene.

We claim:

1. In the dehydrochlorination of 1,2,2,3-tetrachloropropene to obtain 1,2,3-trichloropropene in the presence of an aqueous solution of hydroxides selected from the group consisting of alkali metal hydroxides and alkaline earth metal hydroxides, the improvement which comprises carrying out said dehydrochlorination in the presence of an emulsifying agent having a molecular weight of 264 to 4000 said emulsifying agent being selected from the group consisting of sulfates of alcohols which have from 8 to 17 carbon atoms, phosphates of alcohols which have from 8 to 17 carbon atoms, ethylene oxide adducts of nonyl phenol, ethylene oxide adducts of 2,6,8-trimethyl-4-nonanol and ethylene oxide-propylene oxide adducts of butanol.
20. 2. The process of claim 1 in which the emulsifying agent is an ethylene oxide adduct of nonyl phenol having a molecular weight from 396-1100.
3. The process of claim 1 in which the emulsifying agent is present in the range of 0.1 to 10 percent by weight, based on the 1,2,2,3-tetrachloropropene.
25. 4. The process of claim 1 in which the emulsifying agent is present in the range of 0.5 to 5 percent by weight, based on the 1,2,2,3-tetrachloropropene.
5. The process for the production of 1,2,3-trichloropropene which comprises gradually adding an aqueous solution of sodium hydroxide to a mixture of 1,2,2,3-tetrachloropropene and a nonyl phenol adduct of ethylene oxide having a molecular weight of 396-1100 maintained at a temperature of 100-140° C., said adduct being 30 present in a concentration of 0.1 to 10 percent by weight based on the 1,2,2,3-tetrachloropropene maintaining the vapor temperature at 93-95° C. and removing the 1,2,3-trichloropropene formed.
